HOT AIR FURNACE

Filed March 25, 1929

UNITED STATES PATENT OFFICE

JOHN WINTER, OF ALBION, MICHIGAN

HOT-AIR FURNACE

Application filed March 25, 1929. Serial No. 349,563.

This invention relates to improvements in warm air heating furnaces.

The object of the invention is to provide such a furnace with improved construction of sheet metal radiator for heating the warm air within the furnace casing.

Objects pertaining to details and economies of construction and operation will definitely appear from the description to follow. A furnace embodying the features of my invention is illustrated in the accompanying drawing, in which:

Fig. 1 is a vertical central sectional elevation of a furnace and casing embodying my improvements, taken on line 1—1 of Fig. 2.

Fig. 2 is a horizontal section taken on irregular line 2—2 of Fig. 1.

Fig. 3 is an enlarged sectional view showing details of the heating drum supporting and attaching means.

The parts will be identified by their numerals of reference which are the same in all the views.

1 is the ash pit base. 2 is the firepot. 3 is the combustion chamber made up of superimposed rings with a dome 4, the rings being joined together by joints comprising annular grooves in the top of each ring receiving the lower edge of the superimposed ring or dome. 5 is the furnace casing having the usual top 6. The dome 4 is provided with an outlet pipe 41.

My improved radiator 7 is annular in form and is made of sheet metal having a vertical outer wall 71 and an inturned bottom wall 72 extending in a downturned flange 72' adapted to project into the top groove of the lower combustion chamber ring, see Fig. 3, where the same is secured by suitable cement such as "Smoothon", the same being merely powdered iron.

The top wall 73 is flat and is welded to the vertical inner wall 74 which extends vertically downward straight into the top joint groove of the top ring of the combustion chamber. The inner wall 74 is suitably perforated at 75 for accommodation of the smoke pipe sleeve 41. The smoke pipe sleeve 8 is secured to the outer wall 71 and delivers through the outer casing 5 to the chimney.

A vertical partition wall 76 is between the

aperture 75 and the smoke collar 8 thereby compelling the products of combustion to circulate entirely around through the annular sheet metal radiator before it is discharged at the smoke pipe 8.

A usual clean-out 77 is provided.

The high efficiency of the device is due to its broad radiating surface and free circulation. No direct draft is necessary and I consequently do not provide one. The flow of the heated products of combustion is very free through my improved radiator. Because of the broad surface the heat is very fully given up, resulting in high efficiency. The thin sheet metal is a very effective means of transferring the heat.

I produce my improved radiator from sheet steel and weld the edges thereof together. To accomplish the results to the best advantage I install the same on the furnace in two parts, divided at the joint between the vertical inner wall 74 and the top wall 73 which are held temporarily in place. When the structure is installed and the joints fully formed with the combustion chamber, I weld this last joint by torch or electric weld, making a complete tight structure. The structure, being of sheet metal, is comparatively inexpensive to produce and, while it is made of very thin metal, delivers its heat very rapidly and is consequently subject to unusual erosion it can be very readily renewed and the structure is even then very economical.

I desire to claim it in the specific form shown and also broadly as pointed out in the appended claims.

Having thus described my invention, what I claim as new and desire to secure by Letters Patent, is:

1. In a hot air furnace, the combination with a firepot and combustion chamber made up of ring sections having joints comprising grooved top edges engaging the lower rim of the adjacent ring, of a dome therefor with smoke outlet pipe, an annular sheet metal heat radiator surrounding the top of the said combustion chamber and formed of an outer annular wall, a bottom wall extending inwardly therefrom, and terminating in an attaching flange secured in the top groove of the

combustion chamber top ring, a top wall, and an inner annular wall connected to the top wall and extending downwardly into the joint groove of the top ring of the combustion chamber, said combustion chamber being apertured for the smoke pipe from the dome and being provided with a smoke pipe sleeve and having a vertical partition between the said smoke pipe sleeve and the outlet pipe 10 from the dome to insure flow of products of combustion in the radiator.

2. In a hot air furnace, the combination with a firepot and combustion chamber made up of ring sections having joints comprising 15 grooved top edges engaging the lower rim of the adjacent ring, of a dome therefor with smoke outlet pipe, an annular sheet metal heat radiator surrounding the dome of the said combustion chamber and formed of an outer 20 annular wall, a bottom wall extending inwardly therefrom, a top wall, and an inner annular wall connected to the top wall and extending downwards carried by the wall of the combustion chamber, said combustion 25 chamber being connected by a smoke pipe outlet from the dome and being provided with a smoke pipe sleeve projecting from the radiator and having a vertical partition between the said smoke pipe sleeve and the 30 smoke pipe outlet to insure flow of products of combustion in the radiator.

In witness whereof I have hereunto set my hand.

JOHN WINTER.
